WALL PLAQUE OR SIMILAR ARTICLE
Maurice F. Hoyt, Springfield, Ohio

Application July 28, 1958, Serial No. 51,961

Term of patent 14 years

(Cl. D29—23)

FIG.-1

Figure 1 is a rear perspective view of a wall plaque or similar article showing my new design;

I claim:

The ornamental design for a wall plaque or similar article, substantially as shown.
